(57) **CLAIM**

The ornamental design for an undergarment with built-in sacroiliac belt, as shown and described.

DESCRIPTION

FIG. 1 is a front perspective view of an undergarment with built-in sacroiliac belt, showing the new design, with the undergarment with built-in sacroiliac belt shown being worn, shown from a first side.

FIG. 2 is a front perspective view of the undergarment with built-in sacroiliac belt of FIG. 1, with the undergarment with built-in sacroiliac belt shown being worn, shown from an opposite side.

FIG. 3 is a front perspective view of the undergarment with built-in sacroiliac belt of FIG. 1.

FIG. 4 is a rear perspective view of the undergarment with built-in sacroiliac belt of FIG. 1.

FIG. 5 is a first side view of the undergarment with built-in sacroiliac belt of FIG. 1.

FIG. 6 is an opposite side view of the undergarment with built-in sacroiliac belt of FIG. 1.

FIG. 7 is a front view of the undergarment with built-in sacroiliac belt of FIG. 1, shown unwrapped.

FIG. 8 is a rear view of the undergarment with built-in sacroiliac belt of FIG. 1, shown unwrapped.

FIG. 9 is a front perspective view of another embodiment of the undergarment with built-in sacroiliac belt, showing the new design, with the undergarment with built-in sacroiliac belt shown being worn, shown from a first side.

FIG. 10 is a front perspective view of the undergarment with built-in sacroiliac belt of FIG. 9, with the undergarment with built-in sacroiliac belt shown being worn, shown from an opposite side.

FIG. 11 is a front perspective view of the undergarment with built-in sacroiliac belt of FIG. 9.

FIG. 12 is a rear perspective view of the undergarment with built-in sacroiliac belt of FIG. 9.

FIG. 13 is a first side view of the undergarment with built-in sacroiliac belt of FIG. 9.

FIG. 14 is an opposite side view of the undergarment with built-in sacroiliac belt of FIG. 9.

FIG. 15 is a front view of the undergarment with built-in sacroiliac belt of FIG. 9, shown unwrapped; and,

(Continued)

FIG. 16 is a rear view of the undergarment with built-in sacroiliac belt of FIG. 9, shown unwrapped.

Any broken lines shown, including dashed stitching lines, are directed to unclaimed portions of the undergarment with built-in sacroiliac belt, and form no part of the claimed design. The wavy dash-dot lines are meant to claim that portion of the surface shown in solid lines and with surface shading up to the wavy dash-dot line. The wavy dash-dot line itself represents a boundary line, which boundary line itself forms no part of the claimed design.
